UNITED STATES PATENT OFFICE

CHARLES H. ARNOLD, OF DAYTON, OHIO

LIQUID DISPENSING APPARATUS

Application filed January 7, 1930. Serial No. 330,821.

This invention relates to liquid dispensing apparatus having a measuring pump designed to be driven by a motor. The primary object of the apparatus is to dispense liquid at a much more rapid rate than is possible with hand operated apparatus, and even more rapidly than has been feasible heretofore with motor driven dispensing apparatus.

Another object is to dispense liquid with great accuracy, and to maintain this accuracy regardless of the speed at which the liquid is dispensed. Another object is to surround the operation of the apparatus with safeguards which prevent accidental or intentional manipulation of the controlling devices in an improper sequence. Another object is to dispense quantities of liquid corresponding to a given unit of measurement, or an even multiple of said unit, at each operation of the apparatus, and to provide for postponing the decision as to how many units are to be pumped until within less than one of the desired number of units have been pumped. Another object is to provide for control of the apparatus from a position conveniently near the fuel tank of an automobile, regardless of its position with reference to the apparatus, if it be within the reach of the delivery hose.

In the accompanying drawings,

Fig. 1 is an elevational view, mainly in section, of the pump and parts which operate it, and parts of the operating mechanism;

Fig. 2 is a view of a portion of the mechanism for operating the valve 39 shown in the upper part of the discharge pipe in Fig. 1;

Fig. 3 is a view looking downwardly toward the line 3-3 in Fig. 1, but showing some parts of the operating and controlling mechanism located below this line;

Fig. 4 is a view showing in elevation parts of the operating and controlling mechanism, viewed from the left hand side of Fig. 3;

Fig. 5 is a view of the stop member, detached from associated parts, and

Fig. 6 shows a portion of the indicator, including the two scales carried thereby.

While the apparatus I am about to describe may be used for various purposes, its present embodiment is designed more particularly

for use at filling stations for automobiles, and hereinafter it is to be thought of as pumping gasoline at a filling station. As pumps for filling stations are familiar to everybody I have deemed it unnecessary to illustrate or describe a complete apparatus. It will suffice to describe the portions of the apparatus which my invention concerns.

The pump

The present pump has three cylinders arranged in a circle, 120 degrees apart. In Fig. 1 one of the cylinders is shown in section at 25. The exterior of the upper part of another cylinder is shown at 26, and it is to be understood that the third cylinder of the pump has been cut away in Fig. 1. Immediately below cylinder 25 there is a valve chamber 27, into which gasoline flows from a suction chamber 28. A gravity-actuated check valve 29 prevents the return of gasoline to the suction chamber. Behind the cylinder 25, and not seen in the drawings, there is a chamber into which the cylinder 25 discharges through a port 30, upon the down stroke of its piston 31. In the top of this unseen chamber there is a gravity-actuated check valve, past which the gasoline flows to a discharge chamber, also unseen, and thence through a port 32 to the discharge pipe 33, which is common to the three cylinders. Since said chamber, check valve and discharge chamber are not shown, I refer to the corresponding parts belonging to cylinder 26, which parts are seen at the left of the lower part of Fig. 1. Gasoline discharged from the cylinder 26 passes through the port 34 to the chamber 35, past the valve 36 to the discharge chamber 37, which chamber is in communication through a port 32 with the discharge pipe 33. It is to be understood that there is a valve chamber below cylinder 26 similar to the chamber 27, and that it communicates with the suction chamber 28 through a check valve similar to valve 29. Preferably a strainer 38 is placed in the suction chamber 28. It is to be understood that the discharge pipe 33 continues upward and connects to the usual hose whereby gasoline is put into the fuel tanks of automobiles.

Means for operating the valve 39 in the discharge pipe, and the purpose of the valve, will be explained presently.

Each of the three pistons is provided with a piston rod 40. In the present machine these rods are rectangular in cross section. Journaled on the discharge pipe 33 is a sleeve 41, which carries a double helical cam 42. That is, the portion of the cam which is cut away in Fig. 1 is a complement to the portion shown, with the result that at each revolution of the cam each piston is moved upward and downward once. The piston rods are operatively connected to the cam 42 with rollers 43. The cam 42 is rotated by an electric motor 44, through a train of speed-reducing gears and a clutch. The motor is shown in Fig. 1, secured to the discharge pipe 33. It is to be understood, however, that the motor 20 is not in its proper position; it should be swung around to a position more or less behind the pipe 33. Only two of the gears of the train are shown; these are seen in Fig. 1, namely, the main gear 45 and one of the 25 intermediate gears, 46. The latter is also seen in Fig. 3.

Each cylinder is designed to pump a certain volume of liquid at each stroke. In the present structure the capacity of the cylinders is such that at each cycle of the machine, i. e., each revolution of the cam 42, one-half gallon of liquid is pumped. This, of course, is an arbitrary matter and the parts may be so proportioned as to pump any desired quantity 35 during each cycle.

Operating mechanism

Secured to the upper end of the sleeve 41 is what, for want of a better name, I shall call 40 a stop-member, 50. As will presently appear, this is also a timing or controlling device. Above the member 50 a cam-plate 51 is mounted upon a portion of the sleeve 41 which passes through the member 50. The 45 cam 51 is loose on this extension, so it can rotate with reference thereto. Above the cam-plate 51 a ratchet wheel 52 is revolvably mounted on the pipe 33 and rests upon the upper end of the sleeve 41. Secured to this 50 ratchet wheel is the main gear 45, previously referred to. Referring now to Fig. 3, two pawls, 53—53, will be found mounted on the stop-member 50. These pawls are arranged to be pressed into engagement with the teeth 55 of the ratchet 52 by springs 54—54, which 55 springs are indicated with dotted lines, to avoid obscuring other parts. The pawls are normally held out of engagement with the ratchet by cams 55—55 forming part of the cam-plate 51, which cams engage studs 56—56 60 depending from the pawls. The parts are so shown in Fig. 3. The other ends of the springs are attached to arms 57—57 extending from the cam plate 51, for a reason which 65 will be given presently.

The frame of this machine comprises a member 60, which is attached to other portions of the frame by rods 61. The member 60 is shown in part only, and in Fig. 3 all but a fragment of it is removed. Revolvably mounted on one of the rods 61 is a U-shaped member or lever 62, one leg of the U being above and the other leg below the member 60, with the rod 61 passing freely through each leg. A handle 63 secured to the base of the U is used in moving the member manually. Secured to the upper leg of the U is an arm 64, carrying a roller 65 on its free end. See Fig. 4. A spring 66 tends constantly to draw the end of this arm toward the center of the machine and press the roller 65 against the perimeter of the stop-member 50. This spring also serves to move the member 62 and the handle 63 in one direction, with the result that when the handle is moved manually in the direction indicated by the arrow in Fig. 3 it extends the spring 66, and as soon as the handle is released the member 62, with the several parts attached to it, returns to its normal position, which is that shown in Fig. 3.

Mounted on the lever 62, but elevated above the arm 64, is an arm 67, the free end of which is bifurcated and embraces the depending arm 68 of a bell crank 69. The bell crank is carried by a member 70 attached to the discharge pipe 33, an extension of which member carries the gear 46. See Fig. 1. The horizontal end 71 of the bell crank 69, is connected by a link 72 to an arm 73 whereby the valve 39 is operated. See Fig. 2. When the handle 63 is in the position it occupies in Fig. 3, the valve 39 is closed, as in Fig. 1. The lower leg of the lever 62 is connected by a link 74 to the switch 75 which controls the electric current for the motor 44. The switch is indicated diagrammatically at 75 in Fig. 3. When the handle 63 is in the position it occupies in Fig. 3 the current is cut off from the motor.

Operation of driving and controlling mechanism

Moving the handle 63 clockwise, that is in the direction indicated by the arrow in Fig. 3, does four things, simultaneously: (a) It removes the end of the arm 64 from in front of the lug 76 which projects from the edge of the cam plate 51, allowing the springs 54—54 to rotate the cam-plate clockwise, as it is seen in Fig. 3, thereby removing the cams 55—55 from behind the studs carried by the pawls 53 and allowing the pawls to engage the teeth of the ratchet wheel 52. The rotary movement of the cam-plate is arrested by the cams impinging on the studs which connect the pawls to the stop member 50. (b) It opens the valve 39 in the discharge pipe. (c) It throws on the switch and starts the motor, and (d)

it removes the stop-pawl 64 from engagement with the stop-member 50. Referring to Fig. 5 it will be seen that at one point on its periphery the stop member is provided with a notch 77, which I shall call an abutment, because the roller 65 carried by the arm 64 abuts the portion of this notch which is substantially radial and positively stops the pump at the moment the pawls are lifted from the ratchet wheel. The major part of the periphery of the stop-member is circular, and of sufficient diameter to hold the arm 64 at the point to which it is moved for starting the apparatus. From each end 15 of this circular part the periphery takes a spiral form to meet the notch 77. At the end of any revolution of the stop-member the spring 66 will draw the arm inward and cause the undoing of the four functions 20 which manual operation of the handle performs, unless the handle is manually held in its operative position. Toward the end of any cycle wherein the handle is not held by the operator, the lug 76 impinges on the 25 end of the stop pawl 64, and the cam-plate is thereby arrested. The stop-member continues to move, however, and this relative movement of the stop-member and cam-plate causes the cams 55—55 to lift the pawls from the ratchet wheel at about the instant the stop pawl impinges on the abutment 77 and positively stops the pump. At the same time the motor switch is thrown out, and while the motor armature will coast for a short 30 time, this is unobjectionable, because the motor has been disconnected from the pump by the opening of the clutch (lifting of the pawls 53—53). At the same time the valve 35 is closed, which positively stops the flow of liquid in the discharge pipe. It has been found that where pumps are operated at considerable speed the momentum of the liquid will cause an excessive flow of the liquid, of varying amount, at the end of the operation, causing inaccuracy in the amount of liquid delivered. It is possible that in some cases the delivery hose has a siphoning action. This also is prevented by the valve 39. 40 For operating the machine by hand in an emergency, I provide a stationary stud 80 on which to place a crank, which is not shown. The crank connects to a beveled gear 81, revolvable on the stud. This gear 81 meshes with a second beveled gear, 82, which is connected through the gear 46 to the gear 45.

Quantity indicating mechanism

I provide mechanism for indicating to the customer and to the operator the quantity of gasoline which has been delivered. Inasmuch as one-half gallon of gasoline is delivered at each cycle of the pump, the indicator merely counts the cycles. The visible part of the indicator comprises a cylindrical ring 90, on the outside of which are two graduated

scales; see Fig. 6. This ring is slightly smaller in diameter than the casing which encloses entire mechanism, and at suitable points the casing is provided with sight openings through which to view the graduations. Referring to Fig. 1 the casing is shown in part at 91—91. At 92 a sight opening is formed through which to view the upper scale, while at 93 a sight opening discloses the lower scale. The graduated scales are so positioned on the ring that when any given reading shows through one sight opening the same reading shows through the other opening. The ring is mounted on a series of supporting rollers 94, and held down to its place by a series of retaining rollers 95.

Referring more particularly to Fig. 3 it will be seen that the indicator ring is provided with an internal ratchet wheel 100. For the purpose of moving the ring step by step as the pump operates I provide a pair of levers 101—101, which are mounted on a supporting plate 102 and arranged to rock on studs 103. Each lever carries at one end a pawl 104, which is normally pressed to ratchet wheel 100 by a spring 105, these springs being indicated by dotted lines. At their other ends of the levers carry rollers 106, and these ends of the levers are drawn toward each other by springs 107. The upper end of one of the piston rods 40 is made wedge-shape and upon the up stroke of the piston this wedge-shape end moves between the rollers 106—106 and presses the ends of the levers apart. This causes advance of the right hand pawl 104, as seen in Fig. 3, and the recession of the left hand pawl 104. Upon the down stroke of the wedge the roller-carrying ends of the levers are drawn toward each other by the springs, causing recession of the right hand and advance of the left hand pawl. In this way the ring is advanced step by step, advancing a distance equal to one tooth of the ratchet 100 at each cycle of movement of the pump.

I provide means for resetting the indicator ring to 0 after each sale of gasoline. To the under side of the supporting plate 102 a plate 110 is secured by studs 111. These studs pass through oblique slots 112 formed in the plate 110, to the end that when the plate is moved on the studs it moves in a diagonal path. Depending from each pawl 104 is a stud 113, and when the plate 110 is moved to the left, as seen in Fig. 3, causing the plate to also move toward the pawls, the edge of the plate 110 impinges on the studs 113, and rocking the pawls on their pivots lifts them from the ratchet 100. The edge which engages the studs is scolloped, each scollop being adapted to engage one stud. The ring 90 is provided with an annular flange 114, around which is wrapped a cord 115. See Fig. 4. One end of this cord is attached to the flange 115, while the other end is attached

to and makes a few turns around a sheave 116. See Fig. 3. Connected to this sheave is a second sheave, 117, around which another cord is wound, with its inner end anchored 5 to the sheave. The free end of this cord passes upward and over a sheave 118, carrying a weight 119 at its free end. See Fig. 4. The weight hangs in a tube 120, which tube depends from the frame member 60 and is closed 13 at its lower end. While the weight moves freely in the tube it fits closely enough therein to retard the escape of air from the tube and thus the return of the indicator ring to 0 is effected at a moderate speed.

15 I shall now describe mechanism for operating the pawl-releasing mechanism just described. A vertical shaft 125 is journaled at its lower end in member 60, and at its upper end in the supporting plate 102. See 20 Figs. 3 and 4. An arm 126 rigidly attached to this shaft (see Fig. 4) is attached to the pawl-lifting plate 110 by a slot and pin connection 127. See Fig. 3. Another branch of 25 this arm 126 extends under the ratchet wheel 100, into the path of a stud 128 depending from the wheel. As the indicating ring reaches the 0 on its return after a sale, this stud engages and moves the arm 126, and through the slot and pin connection 127 it 30 moves the pawl-releasing plate 110 to the position it occupies in Fig. 3, thus restoring the indicating mechanism to operative condition.

Another arm, 130, secured to the shaft 125, 35 extends toward the arm 64. Loosely mounted on the shaft 125 is a lever 131, one end of which extends out through the casing 91 of the machine and carries a thumb knob 132. The other end of this lever extends a short 40 distance over the arm 130, and is adapted to engage a stud 133 carried by said arm 130. As seen in Fig. 3, movement of the knob 132 to the left will rock the shaft 125 clockwise, doing two things: (a) lifting the pawls 45 104—104 out of engagement with the ratchet wheel 100, and (b) swinging the arm 130 to the right. This brings the end of the arm 130 into the path of a stud 134 carried by the stop-pawl 64, and prevents operation of the 50 handle 63 to start the machine until after the shaft 125 and the parts it controls have been returned to their normal positions, that shown in Fig. 3, by the stud 128 carried by the indicator. As the lever 131 can only move 55 the arm 130 in one direction this restoration cannot be effected by moving the knob 132 backward. When the handle 63 is operated to start the machine, the stud 134 carried by the stop-pawl 64 moves into the path of the 60 arm 130 and prevents movement of the knob 132 until the pumping operation is stopped.

The operation of the parts of this machine have been so fully described that only a brief resumé is now necessary. When a customer 65 wants gasoline the operator inserts the hose

nozzle into the car tank in the usual way and he then moves the handle 63 to start the machine. He cannot move the handle while the indicator is returning to zero, so unless the indicator is left where it stopped at the last 70 preceding operation, it is always at zero at the beginning of a delivery. The operator must hold the handle in its operative position, else the machine will stop at the end of the cycle during which he releases the handle. Thus there is no danger of his starting the pump and leaving the machine with the pump running, which might result in an overflow of many gallons of gasoline. If the customer has asked for a specified number of 80 gallons the operator holds the handle until the indicator shows that the pump has started to pump the last half-gallon of the amount ordered. He then releases the handle and leaves the mechanism to stop the pump at the 85 proper time. If the customer orders his tank filled the operator watches the tank and releases the handle when the tank is nearly full. The most that will thereafter be pumped will be less than half of a gallon, so even if the 90 tank overflows the amount lost will be small. On the other hand, if the operator finds that the tank will hold still another half gallon he can move the handle to start the machine and immediately release the handle, leaving 95 the machine to stop itself. Having effected a settlement with the customer, or having at least inspected the indicator to find out how much gasoline has been delivered, the operator pushes the knob 132 in the direction of the 10 arrow, and thereafter the resetting of the indicator takes care of itself.

In many cases the handle 63 will be out of the reach of the operator as he stands beside the fuel tank of the customer's car. For this reason I provide for manipulating the handle with a cord 135. This cord is attached to the arm 64, and passing around a sheave 136 the cord passes through a hole in the top of the casing. From there the cord can be conducted by suitable sheaves to the desired position, according to the local conditions. The operator can then start the machine by pulling down on the cord.

I have illustrated and described what I now regard as the preferred mechanical structure wherewith to carry out the purposes of my invention, but it is not to be understood that I limit myself to the specific structure shown, as various modifications are possible without departure from the spirit of my invention and within the scope of the appended claims.

I claim:

1. In a liquid dispenser, a motor, a pump driven thereby, and means for simultaneously disconnecting the motor from the pump, stopping the pump and stopping the flow of liquid to the discharge pipe.

2. In a liquid dispenser, a motor, a pump

- driven thereby, and automatic means for simultaneously disconnecting the motor from the pump, positively stopping the pump and stopping the flow of liquid to the discharge pipe.
3. In a liquid dispenser, a motor, a pump driven thereby, and means for simultaneously disconnecting the motor from the pump, stopping the pump and closing a valve in the discharge pipe.
4. In a liquid dispenser, a motor, a pump driven thereby, and means for positively stopping the pump when a predetermined quantity of liquid has been dispensed, simultaneously disconnecting the motor from the pump and stopping the flow of liquid to the discharge pipe.
5. In a liquid dispenser, a motor, a pump driven thereby, automatic means for simultaneously stopping the pump and positively stopping the flow of liquid therefrom when a predetermined quantity has been pumped, and means whereby predetermination of the quantity to be pumped may be postponed until the desired quantity has nearly been pumped.
6. In a liquid dispenser, a motor, a pump driven thereby, automatic means for stopping the pump and positively stopping the flow of liquid therefrom when a predetermined quantity has been pumped, an indicator showing in units of measurement the quantity that has been pumped during the current operation of the apparatus, means whereby said stopping means is only operative when a unit quantity, or a multiple thereof, has been pumped, and manually operated means for preventing operation of said stopping means at the completion of the current unit quantity.
7. In a liquid dispenser, an electric motor, a pump driven thereby, and means for simultaneously cutting the current off of the motor, positively stopping the pump and stopping the flow of liquid in the discharge pipe.
8. In a liquid dispenser, an electric motor, a pump driven thereby, and means for simultaneously cutting the current off of the motor, disconnecting the motor from the pump, positively stopping the operation of the pump and stopping the flow of liquid in the discharge pipe.
9. In a liquid dispenser, an electric motor, a pump, a clutch for connecting them, which clutch is normally open; a discharge pipe for liquid from the pump, a valve in said pipe, which valve is normally closed; a positive stop for the pump, adapted to stop the pump the instant said clutch is opened, manually operated means for simultaneously closing the clutch, opening said valve, removing said stop and throwing on the motor switch, and a spring for restoring said means to status quo, thereby opening the clutch, closing said valve, stopping the pump and throwing off the motor switch.
10. In a liquid dispenser, a motor, a pump driven thereby through a clutch, a stop-member carried by the pump, a stop pawl carried by a stationary part of the dispenser, and means for opening the clutch when said pawl is thrown into engagement with the stop member.
11. In a liquid dispenser, a motor, a pump driven thereby through a clutch, a stop-member carried by the pump, a stop-pawl adapted to engage said member and stop the pump, means for opening the clutch simultaneously with stopping of the motor by the pawl, and means for simultaneously closing a valve in the discharge pipe of the pump.
12. In a liquid dispenser, a motor, a pump driven thereby through a clutch, a stop-member carried by the pump, a stop-pawl adapted to engage said member and stop the pump, means for opening the clutch simultaneously with stopping of the pump by the pawl, means for simultaneously closing a valve in the discharge pipe, and a timer whereby operation of the aforesaid devices is prevented except when a predetermined quantity of liquid has been pumped.
13. In a liquid dispenser, a motor-driven pump, an indicator showing in units of measurement the quantity of liquid pumped, means adapted to stop the pump after it has pumped a unit quantity, and manually operable means for preventing operation of said stopping means until said indicator shows that the last of a desired number of units of the liquid is being pumped.
14. In a liquid dispenser, a motor-driven pump, an indicator showing the quantity of liquid pumped, means for setting the indicator back to zero after each operation of the pump, means which prevents operation of said back-setting means while the pump is in operation and means for preventing the pump being started while the indicator is returning to zero.
15. In a liquid dispenser, a motor-driven pump, an indicator showing the amount of liquid pumped, means for detaching the indicator from the pump so the former can be reset to zero, and means for resetting the indicator to zero, comprising a weight, said weight being hung in a tube closed at the bottom, thereby trapping air which, escaping slowly, retards the descent of the weight.
16. In a liquid dispenser, a power-driven pump, one cycle of operation of which pumps a quantity of liquid corresponding to a given unit of measurement, an indicator whereby to indicate the cycles operated, and means whereby the pump can be stopped only at the end of a cycle.
17. In a liquid dispenser, a power-driven pump, one cycle of operation of which pumps a quantity of liquid corresponding to a given unit of measurement, an indicator whereby to indicate the cycles operated, and means whereby the pump can be stopped only at the end of a cycle.

6

1,820,931

unit of measurement, an indicator whereby to
show the number of cycles the pump has op-
erated, means whereby the pump can be
stopped only at the end of a cycle, a valve
5 in the discharge pipe, and means whereby
said valve is closed simultaneously with the
stopping of the pump, to the end that the
amount of liquid shall correspond with the
amount shown on the indicator.
